UNITED STATES PATENT OFFICE.

WILLIAM HENRY MILLER, OF GALVESTON, TEXAS.

FIREPROOF WINDOW CONSTRUCTION.

No. 846,682.

Specification of Letters Patent.

Patented March 12, 1907.

Application filed June 22, 1906. Serial No. 322,955.

To all whom it may concern:

Be it known that I, WILLIAM HENRY MILLER, a citizen of the United States, residing at Galveston, in the county of Galveston and State of Texas, have invented certain new and useful Improvements in Fireproof Window Construction; and I do hereby declare the following to be a full, clear, and exact description of the invention, such as will enable others skilled in the art to which it appertains to make and use the same.

My invention relates to improvements in sheet-metal fireproof window construction; and my main object, among others, is to provide a construction of this class whereby the upper sash of the window may be opened and the lower sash held stationary.

A further object is to provide means for removing or replacing the lower sash in the window-frame; and still another object is to provide a suitable frame whereby water or the like will be prevented from entering through the frame or around the sash into the building.

Other objects and advantages will be made clearly apparent in the following specification and pointed out in the claims.

In the accompanying drawings I have shown the preferred form of my invention, and in said drawings, Figure 1 is a perspective view of my improved construction, showing the upper sash in tilted or open position. Fig. 2 is a longitudinal sectional view through the frame and sash, showing portions thereof broken out. Fig. 3 is a perspective view of a portion of my improved structure as seen from the opposite side from that shown in Fig. 1 and with the upper sash closed. Fig. 4 is a sectional view on line 4-4 of Fig. 5. Fig. 5 is an elevation of a portion of the window-frame. Figs. 6 and 7 are detailed sectional views of the horizontal and vertical muntins, respectively, employed in the construction of my improved frame; and Fig. 8 is a detail perspective view of pivot-plate employed in connection with my improved tilting sash.

Like characters designate like parts throughout the several views, and, referring to the numerals on the drawings, 1 indicates a window-frame, said frame being preferably constructed from sheet metal, and is provided near its center with a transom-bar 2,

said transom-bar being provided with ledges 3 and 4 at its upper edge, while the lower edge thereof is cut away to receive the upper rail 5 of a sash 6. The upper edge of the rail 5 is also cut away, and the free edge of the inner face thereof is curved outwardly to form a reinforcing-bead 7, while the free edge of the opposite face thereof is directed outwardly to form a projection 8, said projection being designed to extend over one portion of the transom-bar 2.

The rail 5 is designed to telescope with the transom-bar 2, so that the sash 6 may be elevated to allow the projections 9 and 10 on the lower rail 11 to swing free of the ledges 12 and 13 on the window-sill 14, whereby the sash 6 may be readily placed into or removed from position in the frame. The sash 6 is held firmly within the frame 1 by means of stops 15 and 16, the stop 16 being on the inside of the frame, and extends from the sill 14 to a point above the transom-bar 2 and forms a stop for the lower end of the upper sash 17. The upper sash 17 is designed to be opened by tilting the same in the frame 1, and to this end I have provided supporting-plates 18, which are disposed within the hollow portion of the sash 17 and have at their central portion pivot-stems 19, which are preferably formed integral with the plates and are extended through elongated slots 20 in the side rails of the sash. The stems 19 are adapted to be seated in pivot plates 21, which are secured to the frame 1, said plates having curved ways 22 therein, which are adapted to register with similar ways 23 in the frame 1, the pivot-plates being secured to the face of the frame-wall by rivets or the like, the heads of which are countersunk in the pivot-plates 21, so that a smooth surface will be provided. The ways 22 and 23 extend to the outer face of the frame 1, so that when desired the sash 17 may be readily removed from the frame by releasing the stems 19 from the slots.

The plates 18 are adjustably secured to the frame 17 by disposing cap-screws 24 through elongated slots 25 in the edges of the rails and into engagement with threaded bores in the plates 18, said screws preferably having hexagonal heads, whereby they may be more readily operated. It will therefore be seen that by having the rails provided with an elongated slot that the plates 18 may be

readily adjusted in either direction to properly locate the sash within the frame, and when it is necessary to adjust said plates the cap-screws are loosened, after which the plates are moved to the proper point and the screws again tightened, which will serve to hold the plates in their adjusted position.

By means of the construction just described it will be observed that I have provided a pivot-carrying plate which may be quickly secured to the side of the window-sash and may afterward be readily readjusted, if found necessary, the plate-carrying pivot-point or lug being thus disposed entirely out of the way and out of sight, thus enabling the pivot-point to coöperate with its seating-plate, whereby the sash may be bodily lifted out of the window-frame, as may be desired, and I therefore wish to lay particular stress upon the structural features involved in carrying out this arrangement, and in thus making it possible to provide a pivot-point upon each side of the sash for its support. It has heretofore been common to provide a lug or pivot-point upon each side of the sash; but said lug is not adjustable and is not disposed so that it will be out of sight when the sash is in its operative position in the frame.

30 The upper horizontal rail 26 of the sash 17 is adapted to engage with the projecting ledge 27, formed on the frame 1, the ledge 27 being on the outer edge of the frame, so that when the sash is closed the overhanging edge 28 of the rail 26 will pass between the face of the frame 1 and the overhanging ledge 27, thereby producing a perfect weather-strip for the upper end of the frame.

35 The lower rail of the sash 17 is provided with depending projections 29 and 30, which are adapted to engage the ledges 4 and 5, respectively, of the transom-bar, thereby forming a weather-strip at the lower end of the sash.

40 A controlling-chain 31 is secured to the rail 26 of the sash 17 in any preferred way and is extended downwardly and adapted to be secured to the catch 32, extending from the vertically-disposed muntin 33 on the lower sash 6, so that when the sash 16 is tilted or open, as shown in Fig. 1 of the drawing, one of the links of the chain 31 may be disposed into engagement with the catch 32 and the sash 17 held in its open position.

45 At a point in the chain 32, preferably at the upper end thereof, I provide a fusible link 34, said link being so constructed that it will separate under certain temperature, thereby releasing the sash 17, and as the sash 60 is pivoted above its center said sash will be closed by gravity.

The vertically-disposed muntins 33 consist of a body portion 35, which is disposed be-

tween the panes of glass 36, the inner ends of the body portion 35 being directed along 65 the face of the glass and thence toward each other to form a substantially V-shaped head, upon which is disposed a retaining-strip 37, while over the opposite end of the body 35 is disposed a cap 38, said cap being secured to 70 the body 35 by means of bolts 39 extending through the cap and body and into engagement with a threaded nut 40 between the walls of the body 35.

75 The horizontally-disposed muntins 41 are constructed of two pieces, the body portion 42 thereof having one of its edges prolonged and bent into shape to form the inner section 43, said section 43 being so constructed that it will form shoulders for the lower edges of 80 the glass 36. A cap 45 is disposed over the body 42 and held thereon by means of screws 46, the lower edge of said cap being provided with a plurality of holes 47, so that should water enter between the glass and the upper 85 edge of the cap, it will pass out through the holes in the lower edge thereof.

Referring more particularly to Fig. 4 of the drawing, it will be seen that the rail of the upper sash 17 is so constructed that a way 90 will be formed therein, so that the heads of the cap-screws 24 will not encounter the adjoining face of the frame 1.

What I claim is—

1. The combination with a window-frame 95 having a bar near the center thereof; of a sash in said frame and below said bar, means at the lower end of said sash to coöperate with the frame to form a weather-strip, the upper edge of said sash and the lower edge of said bar being cut away whereby the sash will be telescopically received by the bar.

2. The combination with a window-frame having a transom-bar near its center; of a sash immovably secured in the lower portion 100 of said frame, the upper edge of said sash being cut away, a reinforcing-bead at one edge of said sash, a sash pivotally secured in the upper end of said frame and coöperating means on said tilting sash and frame to form 105 a weather-strip.

3. The combination with a window-frame having a transom-bar near the central portion thereof, the lower portion of said transom-bar being cut away; of a sash stationary 115 in the lower portion of said frame, the upper edge of said sash being cut away whereby said sash may be telescopically entered in the transom-bar, a bead on one edge of said sash, means to retain said sash in the frame, a tilting sash in the upper portion of said frame, means to pivotally secure said sash in the frame, and a projection at the upper end of said sash adapted to engage a portion of said frame and form a weather-strip.

4. The herein-described adjustable carry-

ing-plates for window-sash adapted to be adjustably secured to either side thereof, said plates being countersunk in the edges of the sash and adjustably held in position by retaining-bolts or screws combined with seating-plates having guideways or slots for receiving the lug of the adjustable plate.

In testimony whereof I have signed my name to this specification in the presence of two subscribing witnesses.

WILLIAM HENRY MILLER.
